UNITED STATES PATENT OFFICE.

EDWIN C. MONROE, OF LIBERTY, NEW YORK.

SAWMILL SET-WORKS.

SPECIFICATION forming part of Letters Patent No. 764,484, dated July 5, 1904.

Application filed March 14, 1903. Serial No. 147,828. (No model.)

To all whom it may concern:

Be it known that I, EDWIN C. MONROE, a citizen of the United States, residing at Liberty, in the county of Sullivan and State of New York, have invented new and useful Improvements in Sawmill Set-Works, of which the following is a specification.

My invention has relation to improvements in sawmill set-works; and the object is to improve and simplify the existing art by providing a mechanism for setting the log in its relation to the saw which is simple in construction, accurate in the operation and results, and durable in the uses to which it is adapted.

The invention embodies an operating-wheel having indications of spaces for log movements thereon, a lever to actuate the wheel, measurements predetermined to indicate the scope of the lever movements, and means for restoring the setting mechanism to initial position.

The invention consists in the novel construction of parts and their assemblage or aggregation in operative combination, all as will be hereinafter fully described and the novelty thereof particularly pointed out and distinctly claimed.

It may be prefaced that generally sawmill set-works are provided with ratchet wheels and pawls and are operated by a hand-lever. A figure-board is also provided to indicate the movement of the chain, and indicating-wheel with index-pointers of some description operated by the movement of the ratchet set-wheel. The more complicated the parts which are interposed between the set-wheel and register or indicator the more uncertain and variable will be its work. My improvements are intended to do away with figure-boards and the associated mechanism and substituting therefor a ratchet-wheel to perform and fulfil all the purposes intended. Thus it will be seen that there cannot be any variation when one wheel does all the work and indicates and announces with convenience and certainty the predetermined movement and result.

I have fully and clearly illustrated my invention in the accompanying drawings, to be

taken as a part of this specification, as prescribed by law, and wherein—

Figure 1 is a view in side elevation of the complete apparatus or device. Fig. 2 is a plan view, partly in horizontal section, taken below the ratchet-wheel, showing the lever-supporting table and the return-wheel which reverses the ratchet-wheel and returns it to the initial position. Fig. 3 is a top plan view of the device, showing the lever-table, the lever, and the reversing-gears. Fig. 4 is a plan view of a portion of the setting-wheel whereon are designated the cube designating-blocks and designating-figures to denote the measurements made by the successive revolutions of the setting-wheel. Fig. 5 is a plan view of a setting-wheel whereon are mounted cubes having designated numbers indicating the recurring figures to acquaint the sawyer of the succeeding scales of movement. Fig. 6 is a plan view of a setting-wheel having successive movements of revolution marked thereon. Fig. 7 is a perspective view of one of the indicating-cubes.

In the drawings similar reference notations appearing in the several illustrations designate like parts.

It has not been deemed essential to illustrate the head-blocks and log-beams nor the knees with which the device is associated further than to show the pinion on the lower end of the vertical shaft, which pinion engages with the rack, which moves the knees on the beam to set the log up the required distance. These are all well known, may be of any approved construction, and constitute no part of my invention.

Referring to the drawings, A designates a vertically-arranged hollow cylindrical column or standard of such dimensions as may be required and having a base adapted to be secured to the log-beam in any suitable manner and by any suitable means. In the cylindrical column is rotatably arranged a vertical shaft 1, on the lower end of which is fixedly mounted a pinion 2, adapted to engage with the rack on the knee of the carriage in a well-known manner. The upper end of the vertical shaft 1 extends above the end of the hollow column and has keyed to the extending portion the

horizontally-arranged setting-wheel 3, consisting of a wheel having a determined number of cogs graduated into segmental groups in relation to the pinion and rack, so that a 5 prescribed movement of the setting-wheel will move the log-knee a certain prescribed distance, as will be more fully specified hereinafter.

From the upper portion of the column A 10 projects a table 4, extending in a horizontal plane parallel with the lower face of the setting-wheel and having its outer edge curved concentric to the axis of the setting-wheel, and on this curved edge is marked a scale 5, 15 representing one-half an inch to two inches, so that by placing the inner face edge of the lever on a radial line coincident, for instance, to the score representing one inch and pulling it to the stop the movement will move the set- 20 works one inch. By this means I dispense with all stop-pins except the limit-pin 6, which is stationary and may be made integral with the table.

7 designates a collar secured movably on 25 the column A in line with the upper face of the table, and to this collar is rigidly secured or made integral therewith a lever 8, which extends outward beyond the table and constitutes the means for operating the set-wheel. 30 On this lever is pivotally mounted a pawl 9, which engages the teeth of the set-wheel and turns it with its shaft. To one end of the pawl is secured a rod 10, the outer end of which is suitably connected to the end of a hand-rod 35 11, which is pivotally mounted on the outer end of the lever 8. The set-wheel 3 is formed on its under face with a rack 12, with which a weighted pawl 13 engages, the pawl being hung on the outer end of an arm 14, as indicated in the drawings, and serving to hold the set-wheel in the position to which it may be moved.

To the column A is fixed a horizontally-extending arm 15, having a bearing formed on 45 its outer end, on which is journaled the hub of a face-gear wheel 16, which meshes with an idler-pinion 17, journaled on a bearing 18, formed on or fixed in a vertical arm 19, extending from the arm 15, as shown. A handle 20 is provided to turn the wheel 16. The purpose of this mechanism is to return the set-wheel with its associated parts to the starting-point.

On the edge of the table 4 is fixed a pointer 55 21^a, which indicates to the operator that the desired point of movement of the set-wheel has been reached.

On the face of the rim of the set-wheel 3 are formed or secured a series of cubes 21, 60 having marked thereon figures designating the tooth of the set-wheel with which the pawl 9 is to be engaged to move the wheel to the determined point indicating the cut-line for the saw. The same result may be accomplished 65 by a ring-plate marked with the tooth-desig-

nations; but I prefer the cubes because they present more convenient means for visual observation of the required numbers.

To utilize the device after the log has been shaped by cutting off the slabs it is moved up 70 against the faces of the knees. Then supposing it is intended to saw one-inch boards. All that is necessary is to turn wheel 3 so as to place the nose of the pawl 13 in the tooth which lies or is positioned directly under the tooth 75 which designates the width of the log, say, sixteen inches, and allowing one-quarter inch for the saw-cuts or the thickness of the saw. Then the pawl 9 on the lever would be placed in alinement with the tooth of the setting-wheel 80 bearing the number "14 $\frac{1}{4}$ " and the lever pulled up to the stop 6, thus carrying the knees, with the log, the requisite distance to make the cut. Then in succession the pawl would be set in the teeth numbered "13 $\frac{1}{2}$," "12 $\frac{1}{4}$," "11," 85 "9 $\frac{3}{4}$," "8 $\frac{1}{2}$," "7 $\frac{1}{4}$," "6," "4 $\frac{3}{4}$," "3 $\frac{1}{2}$," "2 $\frac{1}{4}$," and "1."

The sawyer can set the log speedily, because he has only the set-wheel to observe, and the setting is attained with absolute accuracy, because there is nothing to get out of place, the wheel being fast on its shaft and the teeth bearing the correct relation at all times. To expedite the work, after the log has been set and started the pawl may be placed in the next 90 proper tooth while the saw is cutting. By having the figures arranged as shown and the requisite spaces designated thereby it is not necessary to count the number of teeth to ascertain the next place for the engagement of 95 the pawl.

In the present instances shown in the drawings the set-wheel is intended as being seventeen inches in diameter and is provided with ninety-six teeth, so that eight teeth and two 100 teeth for cut shoves the log over to produce a one-inch board.

Having thus fully described the invention, what is claimed as new is—

1. In a sawmill set-works, a setting-wheel 110 having its perimeter provided with a determined number of teeth divided into segmental groups, and cubes mounted on the face of the wheel to designate the boundaries of the groups, said cubes having marked thereon 115 figures to designate corresponding units of advance of the knee by the forward movement of the wheel.

2. In a sawmill set-works, a hollow supporting-column, a vertical shaft mounted rotatably 120 in the column, a pinion on the lower end of the shaft to engage the knee-rack, a setting-wheel mounted on the upper end of the shaft and provided with a determined number of teeth divided into segmental groups, designations on the wheel indicating boundaries of the groups, and a coincident circular rack on its under face, a table supported under the wheel having a curved outer edge concentric to the wheel and a scale on its edge indicating cor- 125 130

responding segmental groups, and a stop projecting vertically therefrom, a lever mounted on the setting-wheel shaft to move on the plane of the table and lodge against said stop, a pawl on the lever to engage the teeth of the set-wheel, whereby when the nose of the pawl engages in a designated tooth of the wheel it

can be moved the distance indicated by the segmental group, and a pawl 13 to engage the circular rack under the setting-wheel.

EDWIN C. MONROE.

In presence of—

BRICE E. SANFORD,
WALLACE M. KILBOURNE.
